UNITED STATES PATENT OFFICE.

PETER A. VANHAUTER, OF LODI, NEW JERSEY.

BURGLAR-ALARM.

1,060,516.

Specification of Letters Patent.

Patented Apr. 29, 1913.

Application filed June 17, 1912. Serial No. 704,177.

To all whom it may concern:

Be it known that I, PETER A. VANHAUTER, a citizen of the United States, residing at Lodi, in the county of Bergen and State of New Jersey, have invented certain new and useful Improvements in Burglar-Alarms, of which the following is a specification, reference being had to the accompanying drawings.

10 This invention relates to improvements in burglar alarms and has for its primary object to provide a simple and efficient electrical alarm device for application to a door or window which will be operated upon an attempt to destroy the device whereby the electrical circuit will be closed and the alarm sounded.

Another object of the invention resides in the provision of an improved switch including pivotally mounted circuit closing members mounted upon the switch base and means for normally holding said switch members out of their effective circuit closing positions, said means including current conducting wires connected to stationary and movable contacts, the circuit being closed through said wires when the contacts are engaged or through the movable switch members when the wires are broken or pulled.

Still another object of the invention resides in the provision of an alarm device of the above character which is extremely simple in its construction, positive and efficient in actual use and may be produced at comparatively small cost.

With the above and other objects in view as will become apparent as the description proceeds, the invention consists in certain constructions, combinations and arrangements of the parts that I shall hereinafter fully describe and claim.

For a full understanding of the invention reference is to be had to the following description and accompanying drawing, in which—

Figure 1 is a side elevation of my improved alarm device showing the circuit connections; and Fig. 2 is a section taken on the line 2—2 of Fig. 1.

Corresponding and like parts are referred to in the following description and designated in the accompanying drawing by like reference characters.

55 Referring in detail to the drawing 5 designates the switch base which may be con-

structed of porcelain, rubber or other suitable insulating material. Upon this base a post 6 is fixed and the similar switch members 7 are pivotally mounted upon this post. 60 These switch members each consist of a body or head 8 which is provided with an opening to receive the post 6. Diverging arms 9 extend from the head 8 of the switch member, and one of these arms is provided with an 65 opening 10 while the other arm has a notch 11 formed therein.

In the switch base 5 a contact post 12 is mounted, and is connected by the wire 13 to one terminal of the battery 14, the other terminal of said battery being connected by a wire 15 to one terminal of a bell or other alarm device indicated at 16. The other terminal of the bell is connected by the wire 17 to the post 6 whereon the movable switch 75 members 7 are mounted.

18 indicates a stationary contact member and 19 a movable contact member. These members may be arranged adjacent to a door, the movable contact being carried by 80 the door, or upon a window sash and frame in any approved manner so as to engage the movable contact with the stationary contact when the door or window is forced open. When applied to the door, the movable contact is so disposed with relation to the stationary contact that the same may be engaged by actuating the movable contact with the finger, the same being preferably in the form of a push button whereby the bell 90 16 may serve the ordinary function of a door bell. To the contact 18 one end of a wire 20 is secured, said wire passing over suitable guides indicated at 21 and through the notch 11 in the arm 9 of one of the movable members 7. The other end of this wire is secured to the contact post 12 as clearly shown in Fig. 1. A similar wire 22 is connected at one end to the movable contact 19 and also passes over guide members and 100 through the notch in the arm of the other switch member 7, said wire having its other end connected to the post 6.

A pair of springs 23 are attached at one of their ends to a bracket or other stationary 105 object and have their other ends engaged in the openings 10 provided in one of the arms of the switch members 7. As shown in the drawings, these springs tend to move the switch members 7 in relatively opposite directions and maintain the wires 20 and 22 in a taut condition. 110

From the above description, the operation of the device will be understood as follows: In the ordinary use of the door bell 16, when the button is pressed to move the contact 19 into engagement with the contact 18, the electric circuit is closed through said contacts, the wires 20 and 22, posts 6 and 12, wires 13, 15 and 17 through the battery 14 to the bell. Should one attempt to destroy the device by breaking the wires 22 or 20, said wires will be pulled, thereby moving one of the switch members 7 against the action of the spring 23 and engaging one of the diverging arms of said member with the contact posts 12. The circuit will thus be closed through said switch member and contact, the post 6 and wire 17 to the bell and from said contact post through the wire 13 to the battery and through the wire 15 from the battery to the other bell terminal. Should either of the wires 20 or 22 be pulled in the attempt to break the same, the circuit will be thus closed. If these wires are cut, the spring 23 will contract and engage the arm of the switch member with which it is connected with the post 12 thereby also closing the circuit and sounding the alarm.

From the foregoing description the construction and manner of operation of the device will be clearly understood. Owing to the simplicity thereof, the entire device may be inconspicuously placed. By the provision of the movable switch members and the connections between the same and the battery and bell, an alarm is produced which is very reliable and efficient in practical use, and which cannot be destroyed by the cutting of the wires, a practice which is commonly resorted to in order to defeat the purpose of such devices.

While I have shown and described the

preferred construction and arrangement of the various elements, it will be understood that the invention is susceptible of considerable modification without departing from the essential features or sacrificing any of the advantages thereof.

Having thus described the invention what is claimed is:

In an alarm device of the character described, a switch base, switch members pivotally mounted on said base, each of said members having a pair of diverging arms, a contact mounted on the base between said arms, springs connected to said members and adapted to move one of the arms of each member into engagement with the contact, an alarm bell, an electric circuit therefor including a battery, circuit connections between the battery and the contact and between the bell and said switch members, stationary and movable contacts, current conducting wires connected to said latter contact and engaged with one of the arms of the switch members, one of said wires being connected to the switch members and the other wire connected to the contact on the switch base whereby the circuit is closed when the stationary and movable contacts are engaged, said wires holding the arms of the switch members out of engagement with the contact on the base against the action of the springs connected to said members, whereby said members are engaged with the contact to close the circuit when the wires are cut or pulled.

In testimony whereof I hereunto affix my signature in the presence of two witnesses.

PETER A. VANHAUTER.
